(57) **CLAIM**

The ornamental design for a decorative strut rail unit, as shown and described.

DESCRIPTION

FIG. 1 is a front elevational view of decorative strut rail showing my new design, the back view being a mirror image;

FIG. 2 is a top plan view thereof;

FIG. 3 is a bottom plan view thereof;

FIG. 4 is an enlarged front end view thereof, the rear end view being a mirror image;

FIG. 5 is an enlarged, exploded view thereof, showing the top bar, bottom bar, and button headed cap screw;

FIG. 6 is a front elevational view similar to FIG. 1, shown on a reduced scale and in position of use as mounted to a motorcycle, which is shown in broken lines for illustrative purposes only and forms no part of the claimed design;

FIG. 7 is an enlarged, partial view of FIG. 6;

FIG. 8 is an enlarged, partial view of FIG. 7; and,

FIG. 9 is an exploded front end view, similar to FIG. 4 on a reduced scale, showing the rear strut, mounting studs, and cap nut in broken lines for clarity of the environmental use of the design and forming no part thereof.
